United States Patent Office

Des. 217,557

Patented May 12, 1970

217,557

CHRISTMAS TREE ORNAMENT

Kurt S. Adler, 1107 Broadway,
Riverdale, N.Y. 10010

Filed Feb. 5, 1969, Ser. No. 15,644

Term of patent 3½ years

Int. Cl. D11—05

U.S. Cl. D29—1

Fig. 1

Fig. 2

Fig. 4

Fig. 3

FIG. 1 is a top plan view of a Christmas tree ornament showing my new design;

FIG. 2 is a front elevational view thereof;

FIG. 3 is a side elevational view thereof; and

FIG. 4 is a bottom plan view thereof.

The sides opposite to those shown in FIGS. 2 and 3 are similar in appearance.

I claim:

The ornamental design for a Christmas tree ornament, substantially as shown and described.
